UNITED STATES PATENT OFFICE.

MORTON L. JOHNSON, OF CHICAGO, ILLINOIS, ASSIGNOR, BY MESNE ASSIGNMENTS, TO
FRANK B. COOK COMPANY, OF CHICAGO, ILLINOIS, A CORPORATION OF ILLINOIS.

TELEPHONE-EXCHANGE SYSTEM.

1,145,245.

Specification of Letters Patent. Patented July 6, 1915.

Application filed July 15, 1912. Serial No. 709,424.

To all whom it may concern:

Be it known that I, MORTON L. JOHNSON, citizen of the United States, residing at Chicago, in the county of Cook and State of Illinois, have invented a certain new and useful Improvement in Telephone-Exchange Systems, of which the following is a full, clear, concise, and exact description, reference being had to the accompanying drawings, forming a part of this specification.

My invention relates to telephone exchange systems and more particularly to that class of telephone exchange systems in which lines extend to two boards of the exchange commonly known as A and B boards. By means of my invention the A operators select the trunks that intervene between the boards and inform the B operators of the selected trunks. I employ selector switches, which may or may not be individual to the trunk lines, for selectively associating the equipment at the operators' positions at the B board with the trunk lines that have been selected at the A board. The B operators may learn from the A board the number of the employed trunk line and the line that is to be called. I have provided means whereby such information may be conveyed independently of the telephone circuits and in this feature of my invention I employ means preferably individual to the trunk lines for creating characteristic signals and operator controlled means for telegraphically sending signals respectively to indicate the numbers of the employed trunk lines and the numbers of the lines that are to be called, suitable signal receivers, which are preferably signal recorders, being distributed among the various positions at the B board, the selectors operatively associating these signal receivers with the trunk lines.

I will explain my invention more fully by reference to the accompanying drawings showing the preferred embodiment thereof and in which—

Figure 1 is a view generally outlining the system of my invention; and Figs. 2, 3 and 4, taken collectively, show more in detail the equipment illustrated in Fig. 1.

Referring first to Fig. 1, I will generally outline the novel features of my invention. The telephone lines extending from stations indicated at 1 are provided with spring jack terminals 2 that are distributed among oper-

ators' positions at what may be termed the A 55 board and which operators may be called A operators. These lines are shown as also extending to the operators' positions at what may be termed the B board where B operators are located. The A and B boards may 60 be in the same building or may be widely separated physically. They form parts of the same telephone exchange system irrespectively of the distance that separates them. The lines from stations 1 are provided 65 with multiplied jacks distributed among the operators' positions at the B board, no multiplied jacks being employed at the A board in the event of the connections being established totally at the B 70 board, though I do not limit myself to this arrangement. I have shown three operators' positions C, D, E at the A board and three operators' positions F, G and H at the B board. The usual cord circuits or link 75 connectors 3 are provided at the operators' positions C, D and E at the A board for connecting the spring jacks 2 of calling lines (calling line signals of lines 1 and jacks 2 being distributed among the operators' positions at the A board) with spring jacks 4 of 80 trunk lines 5 intervening between the A and B boards. The lines 1 extend to the B board and are there provided with multiple jacks 6 at the various sections or operators' positions of such board. The trunk lines 5 are provided with multiple jacks 7 at the positions of the B board. Each B operator is equipped with multiple jacks 6 of the lines 1 and multiple jacks 7 of the trunk lines 5 85 and also has link connectors 8 by which the line jacks 6 and trunk jacks 7 at her position may be connected.

The extension of the lines from stations 1 to the A and B boards, the provision of the 95 line jacks 2 and trunk jacks 4 at the A board, and the provision of the multiple line jacks 6 at the B board are in accordance with telephone exchange systems which are now operated in the United States, especially in the large cities such as Chicago. Hitherto the trunks 5 ended in plugs distributed among the operators at the B board. I preferably modify the existing trunk line equipment by extending the trunk lines to 100 the operators' positions of the B board and employing the multiple trunk jacks 7 at the B operators' positions instead of trunk plug

terminals. I also provide double plug ended link connectors 8 at the B board on account of the substitution of the trunk jacks 7 in place of the trunk plugs. When a call is initiated at the A board, the jack 2 of the calling line at the receiving operators position and a multiple jack 4 of a free trunk line located at such position are connected by a cord circuit 3 at such position. When the 10 selected B operator is made acquainted with the number of the trunk connected with the cord circuit 3 at the A board and the number of the desired line by means of the equipment of my invention to be described, the 15 selected B operator will connect a cord circuit 8 with the multiple jack of the designated trunk line appearing at her position and the multiple jack of the desired line also appearing at her position. Instead of employing order wires between the A and B boards I employ means at the A board whereby the A operators may operate selectors 9, 10 and 11, which are here shown as being individual to the trunk lines 5 but to 20 which individual relationship the invention is not to be limited, these selectors serving to select signal receivers 12 that are located at the operators' positions and which are free for selection and selectively to associate the 25 signal receivers with the trunk lines which the A operators have connected with calling lines 1. The trunk lines are equipped with devices for creating characteristic signals that enable the trunk lines to be distinguished at the B board and the receivers 12 which are selectively associated with the 30 trunk lines serve to receive and preferably to record the characteristic signals so that the operators at the B board will know the 35 trunks that the operators at the A board have selected. The operators at the A board also desirably operate signal receivers, which may be the same receivers 12, so as to inform the operators at the B board of the 40 numbers of the lines desired by the calling parties. The B operator having become acquainted with the number of the trunk line employed by the A operator and having been informed of the number of the desired 45 line proceeds to establish connection between the automatically designated trunk line and the desired line. The telephones 13 and 14 of the A and B operators may be employed in place of the signal receivers 12 to furnish 50 the B operator with the number of the trunk line and the number of the desired line, the B operator's telephone 14 being selected as is the signal device 12, each signal device and each telephone constituting a responsive 55 device common to the link connectors at the corresponding operator's position. Thus a calling station 1 has his line continued through his jack 2, a link connector 3 at the A board, a trunk jack 4 of a free trunk 60 5 selected by the answering A operator, the

trunk jack 7 at the automatically operated B operator's position which belongs to the trunk selected by the A operator, a link connector 8 at the position of the selected B operator, and the multiple jack 6 appearing 70 before the selected B operator and connected with the desired line. The station to be called may be signaled by the B operator by well known signaling apparatus associated with the employed link connector 8. 75

The conductors which lead from the B operators' signal devices 12 and the B operators' telephones 14 are in multiple connection with the waiting contacts of the switches 9, 10 and 11 so that these switches 80 may automatically bring the trunk selected by the A operator into connection or association with the equipment of a B operator who is free to complete connections between the incoming trunks and the desired lines. 85 Each trunk line has a switch arm 15 individual thereto and contacts 16 individual thereto, the elements 15 and 16 individual to each trunk line constituting means for producing a characteristic signal at the selected 90 signal device 12 in a manner to be described. Lines may extend from stations 17 exclusively to the B board where they may be provided with multiple jacks 18. The usual A operator link connectors 19 may be employed for joining the stations 17 with each other and with stations 1 when these latter stations are called. 95

Referring now to Figs. 2, 3 and 4, I will describe my invention more in detail. These 100 figures, taken collectively, illustrate my system and should be arranged in numerical order with the conductors at the tops of the figures in alignment. Each of the two substations 1 and each of the two substations 105 17 is provided with the usual telephone equipment which includes a telephone switch hook 20 having a normal contact for establishing a bridge across the sides of its line that includes a signal bell 21 and a condenser 22 and which switch hook has an alternate contact for establishing another bridge between the sides of its telephone line that includes the telephone transmitter 23 and the telephone receiver 24. The jacks 110 2 at the A board are provided with thimbles 25, tip line springs 26 and sleeve line springs 27. The common battery 28 at the A board, whose illustration is repeated for the sake 115 of clearness, is in normally open circuit relation with a line relay 29 of the associate telephone line. When the telephone receiver 24 is removed at a calling station 1, the two sides of the calling line are metallically connected to establish circuit through 120 the associate line relay whereby the line signal 30 individual to the line is operated. When the A operator answers by inserting 125 the answering plug 31 of a link connector 3 at her position circuit is established through 130

the cutoff relay 32 to restore the line signal 30. The answering A operator then depresses her listening key 33 to include her telephone set 34 in circuit with the calling line to ascertain the number of the line desired. The operator inserts the connecting plug 35 that is companion to the employed answering plug 31 in one of the trunk jacks 4 that belongs to a free trunk line. When 10 the link connector 3 is used for joining the calling line with a trunk line the ringing current generator 36 is not employed, but a signal transmitting key 37 may be employed for the purpose of telegraphing to 15 the B operator that is selected, as herein-after specified, the number of the desired line, the number of the trunk line selected by the A operator being preferably telegraphed to the selected B operator. Instead 20 of telegraphing these numbers the A operator may telephone the numbers to the selected B operator by employing her telephone set 34 and the trunk line which is then brought into telephonic connection with the selected B 25 operator. Each trunk line jack 4 at the A board is associated with a signal 38 individual thereto for denoting the condition of use of the associate trunk line. All of the signals 38 associated with each trunk line 30 are set into operation when any jack 4 of such line is connected with a link connector 3, one terminal of each signal winding being grounded through the common battery 28 while the other terminals of these windings for a given trunk are in multiple connection with normally open contacts 39 at 35 the jacks 4. When a plug is inserted in any jack 4 at the A board the grounded contact 40 at such jack is engaged with a contact 39 so as to ground the multiple connection with 40 the contacts 39 whereby all of the signals 38 associated with a busy trunk are displayed to guard against the intrusion upon such trunk by any other A operator. It will 45 not be necessary to furnish further description of the A board equipment illustrated in Fig. 2 as the various parts and circuit arrangement shown and not specifically described will be readily understood by those 50 skilled in the art.

Figs. 2 to 4, inclusive, show two trunk lines each having B operator selecting apparatus individual thereto, as the invention is illustrated, but to which arrangement the invention is not to be limited. When a trunk jack 4 is plugged into at the A board a circuit is established which may be traced from the grounded connection 41 at the A board through the repeating coil 42, the tip 55 of the connecting plug 35, the tip spring of the jack 4 engaged by said plug, relay 43 through grounded battery which may be the common battery 28. The relay 43 is energized to establish circuit which may be traced from the grounded armature switch 44, the right hand armature switch of relay 43, armature switch of the sluggishly operating interrupter relay 45, the rotary magnet 46, the side switch wiper 47 (in its first position) to the grounded battery 28. 60 On the initial operation of the rotary magnet 46 circuit is established for the private magnet 47', which circuit is maintained as long as the wiper 48 encounters grounded contacts 49. When an ungrounded contact 49 is found the private magnet 47' is de- 65 energized and the side switch wipers 47, 50 and 51 are placed in second positions. When this occurs the rotary magnet is de- 70 energized at 47 so that the wipers 48, 52, 53 and 54 are arrested. The relay 55 is now 75 energized through the side switch wiper 47, the right hand armature switch of the en- 80 ergized relay 43 and the left hand arma- 85 ture switch of the inert magnet 56. The armature switches of relay 55 are now moved to connect wipers 52 and 53 with the talking sides of the trunk that was selected by the A operator and these wipers 52 and 53 are in connection with conductors 57 and 58 that lead to the selected B operator's po- 90 sition where these conductors may be connected with the selected B operator's tele- 95 phone 59 by means of a key 60 at such posi- 100 tion. The side switch wiper 51, in its sec- 105 ond position, established circuit through a relay 61 whose upper armature switch then establishes a circuit through the segmental contact 62, the switch arm 63, the magnet 64, through the interrupter 65 and the 110 grounded battery, which may be the com- 115 mon battery 28 if the A and B boards are located in the same building.

The magnet 64 operates its armature to 115 rotate the wheel 66, the first movement of the wheel 66 establishing contact at 67 for 120 partially closing circuit through a releasing magnet 68, this released magnet circuit being now opened at the lower armature switch of relay 61. The shaft of the wheel 66 carries the switch arm 63 and another switch arm 69, the movement of the wheel 66 occurring as long as the arm 63 engages the contact 62. When contacts 62 and 63 are sepa- 125 rated the magnet 64 is in open circuit caus- 130 ing the wheel 66 to rest. The switch arm 69 passes over telegraphing contacts 70 which are intermittently included by the arm 69 in a circuit which may be traced from these contacts which are grounded through the wiper 54, the contact then engaging the same, the relay 72, to the grounded battery which may be the common battery 28. The relay 72 is intermittently operated to cause 135 the signal receiver 12 to print the number of the trunk line with which the signal receiver 12 has become selectively associated. After the number of the trunk line has been recorded at 12 the A operator supervising the connection will cause the securing of the 140

called line at 12 by way of the circuit which is traceable from the grounded contact of key 37, the heel of the plug 35, the thimble of the jack 4 engaged by said plug, the conductor 73, the contact 74 finally engaged by the arm 69, said arm, the wiper 54, the relay 72 and the grounded battery 28. The selected B operator either in response to the requirements furnished to her by her telephone 59 or by her signal receiver 12, inserts the plug 75 of one of her link connectors 8 into the multiple jack 7 corresponding to the designated trunk 5 and inserts the mate 76 of such plug into the jack 6 (or the jack 18) belonging to the wanted line. Plug 75 when thus inserted in a trunk jack 7, operates to release the actuated automatic selector switch that brought the trunk line selected by the A operator into its association with an idle D operator, a circuit being established which is traced from the grounded battery 28 through the heel of the plug 75, thimble of the jack 7, the winding of relay 56, to ground. Circuit for relay 43 is then opened so that its armatures are restored to normal. The left hand armature switch of relay 43 then establishes a circuit which is traced from ground through said armature switch, the release magnet 77, the now closed off normal switch 78 to the grounded battery 28. The release magnet 77 then restores the wipers 48, 52 to 54, inclusive, and the side switch wipers 47, 50 and 51 to normal position. When the side switch wiper 51 is restored to normal, circuit is opened through magnet 61 whose lower armature switch then completes the circuit through the release magnet 68 to cause the spring 79 to restore the wheel 66 and wipers 63 and 69 to normal, the release circuit being opened at 67 when the wheel 66 reaches normal. The signals 38 of the employed trunk line remain displayed until the plug 75 is withdrawn at the selected B operator's position owing to the connection established between the left hand armature switch of relay 56 and its alternate contact. The supervisory signaling apparatus supplied for the link connectors 3 and 8 is in accordance with well established telephone practice.

The two selector switches shown in detail in Fig. 3 are of similar construction and similar parts are supplied with similar characters of reference. The waiting contacts 55 of the wipers 48, 52, 53 and 54 of the different switches are respectively multiplied. Each operator's conductors 57, 58 leading to her telephone and each conductor leading to her relay 72 is provided with a waiting contact upon each switch, there being as many sets of such waiting contacts as there are operators' positions. Seeking switches are prevented from engaging waiting contacts of previously appropriated conductors 57, 58 by means of a ground established by the

side switch wiper 50 in second position, the ground being connected by way of wipers 48 with the button 49, each switch having such a button individual to each B operator, these buttons being multiplied, such ground maintaining the circuit of private magnet 47 as previously explained. The equipment at the upper part of Fig. 3 differs from the equipment at the lower part in that the contacts 70 associated with the switches are distinguished so as to convey characteristic signals to the receivers 12 when selectively associated therewith.

It is not thought necessary to illustrate the mechanical construction of the automatic switches. Material parts of the mechanism find counter parts in the structure shown upon page 530 of Van Deventer's "Telephonology," published in 1910, the vertical magnets and the movements they effect being omitted. The mechanical construction is further exemplified by reference to British Patent 1298 of 1910.

In my co-pending applications Serial Nos. 709,423 and 709,429, filed of even date herewith I have disclosed means for registering the numbers of calling lines in the presence of receiving operators and selecting mechanism for setting up the digits of calling lines in the presence of receiving operators.

While I have herein shown and particularly described the preferred embodiment of my invention it is obvious that changes may readily be made without departing from the spirit thereof and I do not therefore wish to be limited to the precise details of construction and circuit arrangement shown, but

Having thus described my invention I claim as new and desire to secure by Letters Patent the following:

1. A telephone exchange system including lines extending from telephone stations to different boards of an exchange; trunk lines intervening between these boards; connectors at the boards for connecting the telephone lines with the trunk lines and thereby with each other; operators' signal receivers located at different operators' positions at one of the boards; selector switches associated with the trunk lines for selectively associating said signal receivers that are free to be selected with the trunk lines; means at the other board associated with the trunk lines for setting said selector switches in operation; and means, controlled at the other board, and individual to the trunk lines for creating differentiating characteristic signals by said signal receivers to designate the trunk lines selected at said other board.

2. A telephone exchange system including lines extending from telephone stations to different boards of an exchange; trunk lines intervening between these boards; connectors at the boards for connecting the tele-

phone lines with the trunk lines and thereby with each other; operators' recording signal devices located at different operators' positions at one of the boards; selector switches 5 associated with the trunk lines for selectively associating said operators' recording signal devices that are free to be selected with the trunk lines; means at the other board associated with the trunk lines for 10 setting said selector switches in operation; and means, controlled at the other board, individual to the trunk lines for creating differentiating characteristic signals by said recording signal devices to denote the trunk 15 lines selected at said other board.

3. A telephone exchange system including lines extending from telephone stations to different boards of an exchange; trunk lines intervening between these boards; connectors 20 at the boards for connecting the telephone lines with the trunk lines and thereby with each other; operators' signal receivers located at different operators' positions at one of the boards; selector switches 25 associated with the trunk lines for selectively associating said signal receivers that are free to be selected with trunk lines; means at the other board associated with the trunk lines for setting said selector 30 switches in operation; and means controlled at the other board, and operatively associated with the trunk lines for creating differentiating characteristic signals by said signal receivers to designate the trunk lines 35 selected at said other board.

4. A telephone exchange system including lines extending from telephone stations to different boards of an exchange; trunk lines intervening between these boards; connectors 40 at the boards for connecting the telephone lines with the trunk lines and thereby with each other; operators' recording signal devices located at different operators' positions at one of the boards; selector switches 45 associated with the trunk lines for selectively associating said operators' recording signal devices that are free to be selected with the trunk lines; means at the other board associated with the trunk lines for setting said selector 50 switches in operation; and means, controlled at the other board, and operatively associated with the trunk lines for creating differentiating characteristic signals by said 55 recording signal devices to denote the trunk lines selected at said other board.

5. A telephone exchange system including lines extending from telephone stations to different boards of an exchange; trunk lines 60 intervening between these boards; connectors at the boards for connecting the telephone lines with the trunk lines and thereby with each other; operators' signal receivers located at different operators' positions 65 at one of the boards; selector switches

associated with the trunk lines for selectively associating said signal receivers that are free to be selected with trunk lines; means at the other board associated with the trunk lines for setting said selector switches in operation; and means controlled at the other board for creating differentiating characteristic signals by said signal receivers to designate the trunk lines selected at said other board. 75

6. A telephone exchange system including lines extending from telephone stations to different boards of an exchange; trunk lines intervening between these boards; connectors at the boards for connecting the telephone lines with the trunk lines and thereby with each other; operators' recording signal devices located at different operators' positions at one of the boards; selector switches 80 associated with the trunk lines for selectively associating said operators' recording signal devices that are free to be selected with the trunk lines; means at the other board associated with the trunk lines for setting said selector switches in operation; and means, controlled at the other board, for creating differentiating characteristic signals by said recording signal devices to denote the trunk lines selected at 85 said other board. 95

7. A telephone exchange system including lines extending from telephone stations to different boards of an exchange; trunk lines intervening between these boards; connectors at the boards for connecting the telephone lines with the trunk lines and thereby with each other; operators' signal receivers located at different operators' positions at one of the boards, at which positions the telephone lines and trunk lines are provided with multipled terminals employed in establishing connections there between the telephone lines and the trunk lines; selector switches associated with the trunk lines for selectively associating said signal receivers 100 that are free to be selected with the trunk lines; means at the other board associated with the trunk lines for setting said selector switches in operation; and means, controlled at the other board, and individual to the 105 trunk lines for creating differentiating characteristic signals by said signal receivers to designate the trunk lines selected at said other board. 110

8. A telephone exchange system including lines extending from telephone stations to different boards of an exchange; trunk lines intervening between these boards; connectors at the boards for connecting the telephone lines with the trunk lines and thereby 115 with each other; operators' recording signal devices located at different operators' positions at one of the boards, at which positions the telephone lines and trunk lines are provided with multipled terminals em- 120

ployed in establishing connections there between the telephone lines and the trunk lines; selector switches associated with the trunk lines for selectively associating said operators' recording signal devices that are free to be selected with the trunk lines for setting said selector switches in operation; and means, controlled at the other board, and individual to the trunk lines for creating differentiating characteristic signals by said recording signal devices to denote the trunk lines selected at said other board.

9. A telephone exchange system including lines extending from telephone stations to different boards of an exchange; trunk lines intervening between these boards; connectors at the boards for connecting the telephone lines with the trunk lines and thereby with each other; operators' signal receivers located at different operators' positions at one of the boards, at which positions the telephone lines and trunk lines are provided with multiplied terminals employed in establishing connections there between the telephone lines and the trunk lines; selector switches associated with the trunk lines for selectively associating said signal receivers that are free to be selected with trunk lines; means at the other board associated with the trunk lines for setting said selector switches in operation; and means controlled at the other board, and operatively associated with the trunk lines for creating differentiating characteristic signals by said signal receivers to designate the trunk lines selected at said other board.

10. A telephone exchange system including lines extending from telephone stations to different boards of an exchange; trunk lines intervening between these boards; connectors at the boards for connecting the telephone lines with the trunk lines and thereby with each other; operators' recording signal devices located at different operators' positions at one of the boards, at which positions the telephone lines and trunk lines are provided with multiplied terminals employed in establishing connections there between the telephone lines and the trunk lines; selector switches associated with the trunk lines for selectively associating said operators' recording signal devices that are free to be selected with the trunk lines for setting said selector switches in operation; and means, controlled at the other board, for creating differentiating characteristic signals by said recording signal devices to denote the trunk lines selected at said other board.

11. A telephone exchange system including lines extending from telephone stations to different boards of an exchange; trunk lines intervening between these boards; connectors at the boards for connecting the tele-

phone lines with the trunk lines and thereby with each other; operators' signal receivers located at different operators' positions at one of the boards, at which positions the telephone lines and trunk lines are provided with multiplied terminals employed in establishing connections there between the telephone lines and the trunk lines; selector switches associated with the trunk lines for selectively associating said signal receivers that are free to be selected with trunk lines; means at the other board associated with the trunk lines for setting said selector switches in operation; and means controlled at the other board for creating differentiating characteristic signals by said signal receivers to designate the trunk lines selected at said other board.

12. A telephone exchange system including lines extending from telephone stations to different boards of an exchange; trunk lines intervening between these boards; connectors at the boards for connecting the telephone lines with the trunk lines and thereby with each other; operators' recording signal devices located at different operators' positions at one of the boards, at which positions the telephone lines and trunk lines are provided with multiplied terminals employed in establishing connections there between the telephone lines and the trunk lines; selector switches associated with the trunk lines for selectively associating said operators' recording signal devices that are free to be selected with the trunk lines; means at the other board associated with the trunk lines for setting said selector switches in operation; and means controlled at the other board, and operatively associated with the trunk lines for creating differentiating characteristic signals by said recording signal devices to denote the trunk lines selected at said other board.

13. A telephone exchange system including lines extending from telephone stations to different boards of an exchange; trunk lines intervening between these boards; connectors for connecting the telephone lines with the trunk lines and thereby with each other; operators' signal receivers common to the trunk lines and located at different operators' position at one of the boards; and means controlled at the other board and individual to the trunk lines for creating differentiating characteristic signals by said signal receivers to designate the trunk lines selected at said other board.

14. A telephone exchange system including lines extending from telephone stations to different boards of an exchange; trunk lines intervening between these boards; connectors for connecting the telephone lines with the trunk lines and thereby with each other; operators' recording signal receivers located at different operators' positions at one of the boards; and means controlled at

the other board and individual to the trunk lines for creating differentiating characteristic signals by said signal receivers to designate the trunk lines selected at said other board.

- 5 15. A telephone exchange system including lines extending from telephone stations to different boards of an exchange; trunk lines intervening between these boards; connectors for connecting the telephone lines with the trunk lines and thereby with each other; an operator's signal receiver common to the trunk lines and located at an operator's position at one of the boards; and means controlled at the other board and individual to the trunk lines for creating differentiating characteristic signals by said signal receiver to designate the trunk lines selected at said other board.

- 10 20. 16. A telephone exchange system including lines extending from telephone stations to different boards of an exchange; trunk lines intervening between these boards; connectors for connecting the telephone lines with the trunk lines and thereby with each other; an operator's recording signal receiver located at an operator's position at one of the boards; and means controlled at the other board and individual to the trunk lines for creating differentiating characteristic signals by said signal receiver to designate the trunk lines selected at said other board.

- 15 25. 17. A telephone exchange system including lines extending from telephone stations to different boards of an exchange; trunk lines intervening between these boards; connectors for connecting the telephone lines with the trunk lines and thereby with each other; operators' signal receivers common to the trunk lines and located at different operators' positions at one of the boards; and means controlled at the other board for creating differentiating characteristic signals by said signal receivers to designate the trunk lines selected at said other board.

- 30 35. 18. A telephone exchange system including lines extending from telephone stations to different boards of an exchange; trunk lines intervening between these boards; connectors for connecting the telephone lines with the trunk lines and thereby with each other; operators' recording signal receivers located at different operators' positions at one of the boards; and means controlled at the other board for creating differentiating characteristic signals by said signal receivers to designate the trunk lines selected at said other board.

- 35 40. 19. A telephone exchange system including lines extending from telephone stations to different boards of an exchange; trunk lines intervening between these boards; connectors for connecting the telephone lines with the trunk lines and thereby with each

other; an operator's signal receiver common to the trunk lines and located at an operator's position at one of the boards; and means controlled at the other board for creating differentiating characteristic signals by said signal receiver to designate the trunk lines selected at said other board.

- 45 50. 20. A telephone exchange system including lines extending from telephone stations to different boards of an exchange; trunk lines intervening between these boards; connectors for connecting the telephone lines with the trunk lines and thereby with each other; an operator's recording signal receiver located at an operator's position at one of the boards; and means controlled at the other board for creating differentiating characteristic signals by said signal receiver to designate the trunk lines selected at said other board.

- 55 60. 21. A telephone exchange system including lines extending from telephone stations to different boards of an exchange; trunk lines intervening between these boards; connectors for connecting the telephone lines with the trunk lines and thereby with each other; operators' signal receivers located at different operators' positions at one of the boards; selector switching mechanism for interchangeably associating idle signal receivers with the trunk lines; and means controlled at the other board and individual to the trunk lines for creating differentiating characteristic signals by said signal receivers to designate the trunk lines selected at said other board.

- 65 70. 22. A telephone exchange system including lines extending from telephone stations to different boards of an exchange; trunk lines intervening between these boards; connectors for connecting the telephone lines with the trunk lines and thereby with each other; operators' recording signal receivers located at different operators' positions at one of the boards; selector switching mechanism for interchangeably associating idle signal receivers with the trunk lines; and means controlled at the other board and individual to the trunk lines for creating differentiating characteristic signals by said signal receivers to designate the trunk lines selected at said other board.

- 75 80. 23. A telephone exchange system including lines extending from telephone stations to different boards of an exchange; trunk lines intervening between these boards; connectors for connecting the telephone lines with the trunk lines and thereby with each other; an operator's signal receiver located at an operator's position at one of the boards; selector switching mechanism for interchangeably associating an idle signal receiver with the trunk lines; and means controlled at the other board and individual to the trunk lines for creating differentiat-

ing characteristic signals by said signal receiver to designate the trunk lines selected at said other board.

24. A telephone exchange system including lines extending from telephone stations to different boards of an exchange; trunk lines intervening between these boards; connectors for connecting the telephone lines with the trunk lines and thereby with each other; an operator's recording signal receiver located at an operator's position at one of the boards; selector switching mechanism for interchangeably associating an idle signal receiver with the trunk lines; and means controlled at the other board and individual to the trunk lines for creating differentiating characteristic signals by said signal receiver to designate the trunk lines selected at said other board.

25. A telephone exchange system including lines extending from telephone stations to different boards of an exchange; trunk lines intervening between these boards; connectors for connecting the telephone lines with the trunk lines and thereby with each other; operators' signal receivers located at different operators' positions at one of the boards; selector switching mechanism for interchangeably associating idle signal receivers with the trunk lines; and means controlled at the other board for creating differentiating characteristic signals by said signal receivers to designate the trunk lines selected at said other board.

26. A telephone exchange system including lines extending from telephone stations to different boards of an exchange; trunk lines intervening between these boards; connectors for connecting the telephone lines with the trunk lines and thereby with each other; operators' recording signal receivers located at different operators' positions at one of the boards; selector switching mech-

anism for interchangeably associating idle signal receivers with the trunk lines; and means controlled at the other board for creating differentiating characteristic signals by said signal receivers to designate the trunk lines selected at said other board.

27. A telephone exchange system including lines extending from telephone stations to different boards of an exchange; trunk lines intervening between these boards; connectors for connecting the telephone lines with the trunk lines and thereby with each other; an operator's signal receiver located at an operator's position at one of the boards; selector switching mechanism for interchangeably associating an idle signal receiver with the trunk lines; and means controlled at the other board for creating differentiating characteristic signals by said signal receiver to designate the trunk lines selected at said other board.

28. A telephone exchange system including lines extending from telephone stations to different boards of an exchange; trunk lines intervening between these boards; connectors for connecting the telephone lines with the trunk lines and thereby with each other; an operator's recording signal receiver located at an operator's position at one of the boards; selector switching mechanism for interchangeably associating an idle signal receiver with the trunk lines; and means controlled at the other board for creating differentiating characteristic signals by said signal receiver to designate the trunk lines selected at said other board.

In witness whereof, I hereunto subscribe my name this third day of July A. D., 1912.

MORTON L. JOHNSON.
